LEBBEUS H. ROGERS, OF NEW YORK, N. Y.

PNEUMATIC COMPRESSOR.

No. 800,765.

Specification of Letters Patent.

Patented Oct. 3, 1905.

Application filed December 29, 1904. Serial No. 238,821.

To all whom it may concern:

Be it known that I, LEBBEUS H. ROGERS, of New York, State of New York, have invented a new and useful Improvement in 5 Pneumatic Compressors, which invention is fully set forth in the following specification.

This invention relates to pneumatic compressors, especially to rotary air-compressors in which considerable oil is used in and 10 about their moving parts, and to means whereby such oil and parts may be warmed when the surrounding temperature is below that necessary for effective operation of the compressor.

15 Air-compressors of the type above referred to find application in connection with air-brake systems on street-cars and railway-trains, where they are used to compress air in the main air-reservoir. In certain forms of 20 such compressors oil is used within the compressor, which in cold weather is apt to congeal during periods of rest. While the compressor is in operation, however, sufficient heat is produced by the friction of the 25 pistons and other movable parts to maintain the oil in the compressor in a fluid state even in severe cold weather; but when such compressors are used in connection with automatic controllers which stop the operation of 30 the compressor when a predetermined pressure is reached in the compressed-air reservoir the oil in the compressor may become viscous and congeal during the time of inaction of the compressor in severe cold weather. In 35 the case of street-railway cars, which are run into a cold barn for several hours during the night, this objectionable phenomenon frequently occurs. By morning the oil becomes too viscous and often congealed to 40 permit the compressors to be immediately used or permit the cars to be run onto the road for service. It therefore becomes necessary for each car carrying a compressor to be detained in the morning in the coldest 45 weather till the men tending the cars can warm up each compressor by aid of torches or lamps to the point where the congealed oil becomes fluid, after which friction of the moving parts during operation of the 50 compressor will keep the oil in working condition.

To avoid the above objections and reduce the time and amount of labor required in putting such compressors into operation during periods of low temperature, I have devised means whereby heat may be instantly applied to the interior of the compressor to

raise the temperature within the same to a proper temperature for its operation, and this is accomplished by placing within the interspaces of the piston-carrying drum suitable heating devices, but preferably electric heating devices, as hereinafter described, and specifically pointed out in the claims.

In the accompanying drawings I have shown, for the purpose of illustration, the best embodiment of the invention known to me, in which—

Figure 1 is a vertical section through an air-compressor provided with my improvement. Fig. 2 is a vertical cross-section of the same, taken on the line 2 2 of Fig. 1 looking toward the right, while Fig. 3 shows diagrammatically a plurality of heaters controlled by a single switch.

Referring to the drawings, 1 is the outer casing of rotary air-compressor of the type described in my copending application, Serial No. 223,913, filed September 9, 1904. So much of the same is herein described as will suffice to show the connection of the invention therewith. Casing 1 is preferably provided at one end with an integral head 2; at the other end with a removable head 3, which is secured to the casing in any well-known or suitable manner. Projecting from each head are bearings 4 5 for supporting a revoluble shaft 6, which makes a tight joint with the bearings 4 and 5 by stuffing-boxes 7 8. Fast to shaft 6 is a drum 9, and fast to the ends of drum 9 are rings 10 11, which partially close the ends of the drum and are secured thereto by screws 12. At the left-hand end of the cylinder 1 is a plate 13, secured to the cylinder and provided with openings 14, which communicate with an oil-receiving space 15, formed in the integral end of the cylinder.

In Fig. 2 is shown an oil-supply reservoir 16, which is adapted to deliver oil through pipe 17 to a channel 18 in the head 2, leading to space 15, and thence through openings 14 to portions of the interior of the drum 9. This drum is divided longitudinally into one or more compression-chambers 19, having parallel walls which guide the air-compressing pistons 20, as they are made to reciprocate by any suitable means, such as by cams 21, at the end of each of the pistons 20, running in cam-grooves 22 23, eccentric to the axis of the cylinder 9. The rotation of the shaft 6 causes the drum 9 to rotate, carrying with it the pistons 20, whose cams 21 travel

in cam-grooves 23, causing the pistons during one half-revolution of the drum to draw in air at 24 and compress it during the other half-revolution through exit 25. The space 5 back of the pistons and also the quadrangular spaces 27 between the piston-channels are filled with oil supplied from tank 16. When the temperature of the oil lowers sufficiently, as it is apt to do in cold weather, it 10 becomes viscous and even congeals, interfering with the movement of the pistons, and it is for the purpose of avoiding the usual delay in heating up the whole compressor that I have provided the piston-carrying drum 15 with means for locally heating the oil in the drum, and to this end I preferably place an electric heating-coil 28 in each of the spaces 27 and connect them either in series or parallel with insulated conductors 29 and 30, 20 which are in metallic contact with slip-rings 31 and 32, respectively. These rings are insulated from the shaft 6 by non-conducting material, such as mica or like material, (shown at 33 and 34.) Brushes 35 36 connect 25 the rings and the coils connected to them with a source of current, such as a battery, or to the mains. When these compressors are located upon an electric car or train, the brushes are connected to a switch 30 within easy reach of the attendant. Where a number of cars are in a single shed or barn, temporary electric connections may be made from each compressor to a central switch, whereby all the heaters may be simultaneously 35 operated by one person. In Fig. 3 there is shown diagrammatically two such compressors 11, each located beneath its car and temporarily connected through suitable leads from switch 37 to a central switch 40, 40 adapted to close a circuit through the heating coils and mains 38 39, which latter are to be located in the car shed or barn in convenient proximity to the cars. On closing switch 40 and any one or all of switches 37 45 one or all the compressors may be heated.

The operation of the heating device will be readily understood from the preceding description and drawings. During the cold weather the cars remain during the night in 50 cold barns or even in the open, during which time the oil in the compressors is often chilled to a degree which renders it viscid and even semicold. Before running the cars out for the day it was necessary heretofore 55 for the attendant to warm each compressor by a torch or lamp to render the oil sufficiently fluid for the proper working of the compressor. By aid of the above-described improvement it is only necessary to turn on 60 the current through the heating-coils by means of an electric switch, which may control the current to one or many compressors. Heat is thereby instantly applied to all the compressors simultaneously. This results 65 in a great saving of time and labor during the

cold weather each time the cars are started out for the day's run.

Although I have described this invention in relation to rotary pneumatic compressors, yet it is equally applicable to pumps and other forms of compressors where the parts run in oil and to such devices where the viscosity of the oil is to be overcome by heat, and I do not limit my invention to the precise construction and arrangements shown, 70 as changes in construction or arrangement may be made without departing from the spirit of my invention.

What is claimed is—

1. In combination, a pump, an oil-supply 80 reservoir for the same, and means within the pump for heating the oil.
2. In combination, a pump, an oil-supply reservoir for the same, and electric heating means within the pump. 85
3. In a pump, a revoluble piston-carrying drum and heating means within the drum.
4. In combination, a pump having oil-receiving spaces therein and heating means within the pump. 90
5. In combination, a compressor-pump having an oil-receiving space therein and electric heating means in said space. 95
6. In a pump, a revoluble piston-carrying drum, electric heating means in the drum, leads located in the axis of the drum and connected to said heating means, and contact-rings connected to said leads. 100
7. In a pump, a revoluble piston-carrying drum, a shaft supporting the same, electric 100 heating means in the drum, leads in the shaft in circuit with said heating means, and slip-rings on said shaft connected to said leads.
8. In an air-compressor pump, a revoluble piston-carrying drum, oil-receiving spaces in said drum, electric heating means carried by said drum, and means for connecting said heating means with a source of electric current. 105
9. In an air-compressor pump, a revoluble piston-carrying drum having oil-spaces within the same, electric heating-coils in said spaces, and means for connecting said heating means with a source of electric current. 110
10. In an air-compressor pump, a revoluble piston-carrying drum having oil-spaces within the same, a shaft for rotating said drum, electric heating means in said oil-spaces, leads in said shaft connected in parallel with said electric heating means, and slip-rings on said shaft connected to said leads. 115
11. In a system of heating pneumatic compressors on cars, a plurality of said compressors, electric heating means within each compressor, a source of current-supply, and means for connecting the same with each of said heaters, and a single switch for controlling current to all the heaters. 125

12. In combination, a pneumatic compressor for cars, electric heating means within the compressor, a source of current-supply, means for connecting the same with said heater, and a switch on the car for controlling current to said heater.

5 In testimony whereof I have signed this

specification in the presence of two subscribing witnesses.
